UNITED STATES PATENT OFFICE

MORTON GOLDSHOLL, OF CHICAGO, ILLINOIS

DESIGN FOR A POCKET KEYHOLDER

Application filed December 30, 1932. Serial No. 46,668. Term of patent 14 years.

To all whom it may concern:

Be it known that I, MORTON GOLDSHOLL, a citizen of the United States, residing at Chicago, in the county of Cook and State of Illinois, have invented a new, original, and ornamental Design for Pocket Keyholders, of which the following is a specification, reference being had to the accompanying drawing, forming part thereof.

Figure 1 is a side view of a pocket keyholder showing my new design and Figure 2 is an end view of the same.

I claim:

The ornamental design for a pocket keyholder as shown.

MORTON GOLDSHOLL.
